UNITED STATES PATENT OFFICE.

THOMAS B. ROGERS, JR., OF BROOKLYN, NEW YORK, ASSIGNOR TO MAX HALLHEIMER, OF SAME PLACE.

IMPROVEMENT IN SHUTTER AND DOOR FASTENERS.

Specification forming part of Letters Patent No. 175,381, dated March 28, 1876; application filed February 21, 1876.

To all whom it may concern:

Be it known that I, THOMAS B. ROGERS, Jr., of Brooklyn, in the county of Kings and State of New York, have invented a new and Improved Adjuster and Fastener for Doors, Window-Blinds, and other objects, of which the following is a specification:

My invention consists of a couple of bars, of unequal length, which are jointed together at one end, and one is jointed to the window or door, and the other to the window-sill or door-frame, so that they swing with the door or blind, and at the joint of the bars is a clamp by which the joint can be readily made rigid to fasten them and hold the door or blind in any position; and besides the clamp there is a stud at the joint which drops into a socket in the sill to fasten the blind or door shut. The two bars are of different lengths, so that where they come together by the closing of the door or window they will prevent the opening of the same from the outside without being clamped at the joint, by the counteraction of the one on the joint of the other due to their different radii, as will be hereinafter more fully described.

Figure 1 is a horizontal section of a window-blind with my improved adjuster and fastener, the blind being shut. Fig. 2 is a similar section with the blind partly open, the two sections being taken on line *x x* of Fig. 2. Fig. 3 is a sectional elevation, taken on line *y y* of Fig. 2.

Similar letters of reference indicate corresponding parts.

A is the blind; B, the sill; C, the bar pivoted to the latter, and D the bar pivoted to the blind. These bars are coupled at E by a clamp-screw, F, and a thumb-nut, G, and they have corrugated bearing-surfaces H by which they lock so firmly together that they hold the blind or door in any partly open position, as represented in Fig. 2. Besides the coupling

at E there is a stud, I, which drops into a hole, K, in the sill as a further means of securing the blind closed, and another element of security lies in the different lengths of the two bars, which prevents the blind or door from swinging outward until the joint E is swung inward from the hole K to a certain extent, as represented in Fig. 2. L is a hook attached to the blind for hooking onto the stud M, as represented in Fig. 3, when the blind is shut.

This improved fastener and adjuster may be used for other objects besides doors and blinds, for instance, trunk-lids, fan-lights, &c.

N is another hook attached to the blind to hook on the stud M when the blind is open to fasten the parts in that position. This hook swings on a horizontal pivot, O, and it has a stop, P, on each side to prevent it from falling so low as to strike against the bars when closing, and to keep it up in the best position for handling it.

Having thus described my invention, I claim as new and desire to secure by Letters Patent—

1. The bars C D, of unequal length, and clamp-joint E, combined with a door-shutter or window-blind, and the door-sill, window-sill, or frame B, substantially as specified.

2. The stud I, in combination with clamp-joint E, of bars C D, and the blind or door and frame, substantially as specified.

3. The catches L N on the blind or door, with stud M on bar D in such manner as to lock with it both when closed and open, substantially as specified.

4. The stops P, combined with hook L or N, to hold it above the bars, substantially as specified.

THOMAS B. ROGERS, JR.
